(57) **CLAIM**

The ornamental design for a computer monitor picture frame, as shown and described.

DESCRIPTION

FIG. 1 is a front elevational view of a computer monitor picture frame showing our new design;

FIG. 2 is a right side elevational view thereof;

FIG. 3 is a left side elevational view thereof;

FIG. 4 is a top view thereof;

FIG. 5 is a rear elevational view thereof; and,

FIG. 6 is a front perspective view thereof.

Computer monitor is shown in broken lines for illustrative purposes only and forms no part of the claimed design.
